UNITED STATES PATENT OFFICE.

HUGH WALLACE AITKEN, OF GLASGOW, SCOTLAND.

SUGAR-CANE MILL.

1,184,294.

Specification of Letters Patent.

Patented May 23, 1916.

Application filed March 16, 1915. Serial No. 14,674.

To all whom it may concern:

Be it known that I, HUGH WALLACE AITKEN, a subject of the King of Great Britain and Ireland, residing at Richmond Chambers, 147 Bath street, Glasgow, Scotland, have invented certain new and useful Improvements in Sugar-Cane Mills; and I do hereby declare the following to be a full, clear, and exact description of the invention, 10 such as will enable others skilled in the art to which it appertains to make and use the same, reference being had to the accompanying drawings, and to letters or figures of reference marked thereon, which form a 15 part of this specification.

My invention relates to sugar cane mills of the usual three-roller type. In such mills it is usual to provide means for adjusting the bearings of the side rollers in a horizontal direction. Alternatively, however, means 20 have been provided, or proposed, for adjusting the side roller bearings in a vertical direction, or in a definite oblique direction (e. g., in a line joining the axes of the top 25 and side rollers) instead of in a horizontal direction. It is, in my opinion, of immense advantage in a three roller sugar cane mill to be able to adjust the side rollers with respect to the dumbturner without altering the 30 clearances between the top roller and the side rollers, and to be able to adjust these clearances (between top roller and side rollers) without affecting the relationship between the side rollers and the dumbturner. 35 In my opinion it is only possible to obtain these effects and to derive the maxima of the advantages obtainable from adjustment of the side rollers by providing means for adjusting the positions of the bearings of these 40 rollers in two directions approximately at right angles to each other, e. g., in a horizontal direction and in a vertical direction.

My invention—which will be described in the following specification and more particularly defined in the annexed claims—has 45 for its object the securing of these advantages.

The accompanying drawings will serve to illustrate my invention.

50 Figure 1 is an elevation—partly in section—of a mill headstock showing the means for adjusting one of the side roller bearings according to my invention. Fig. 2 is an end elevation of Fig. 1.

55 In Figs. 1 and 2, *a* is the mill headstock, *b*, *b*, *b*, indicate the three rollers, *c* is the

journal of the side roller at the admission side of the mill, *d* is the bearing for this journal, *e* is the cap which holds in the bearing, and *f*, *f* are the bolts which secure this 60 cap. The bottom of the recess in the headstock which receives the bearing is provided with an inclined surface *g* and, engaging with this inclined surface, is a wedge block *h* on which the bearing rests. This wedge 65 block can be pushed in by means of pinching screws *k* which work in nuts *m* which are recessed into the cap.

o is a large pinching screw which works in a nut *p* recessed into the cap and is adapted 70 to act on the plate or bolster block *q* placed behind the bearing. By means of this large pinching screw the bearing can be pushed forward or inward. The plates *s*, *t* are of hard steel and are let into the block *q* and 75 wedge *h* for the purpose of receiving the pressure of the pinching screws. The bearing can be adjusted vertically by means of the wedge *h*; it can be adjusted horizontally by means of the pinching screw *o*; and it 80 can be adjusted in any other direction by the joint action of the wedge *h* and pinching screw *o*. The bearing can thus be adjusted in any desired direction, and, within 85 certain limits, to any desired extent.

It will be obvious that the wedge could be arranged in any one of four different ways. For example, it could be arranged (1) with the upper surface horizontal, the lower surface inclined, and the larger end 90 at the outside (as in Fig. 1); (2) with the upper surface horizontal, the lower surface inclined, and the larger end at the inside (as in Fig. 3); (3) with the upper surface inclined (the bush being then formed with an inclined lower surface), the bottom surface horizontal (the headstock being then formed with a horizontal surface to receive the wedge), and the larger end at the outside; 95 (4) same as 3 but with the larger end at the inside.

By means of my invention it is possible to adjust the side roller at the inlet side of the mill for wear of the dumbturner without altering the normal space or gap between this roller and the top roller. It is also possible to adjust and maintain the back of the dumbturner to be at the required distance from the megasse roller (that is the roller at the outlet side of the mill). This 105 point is of importance, especially in the last mills of a series, as too much space allows 110

megasse to fall through, and too little space allows inadequate area for the escape of juice.

I have deemed it unnecessary to illustrate or describe in greater detail the location and function of the dumbturner, as this will be familiar to those skilled in the art.

It is not necessary that the two directions of adjustment should be exactly horizontal and exactly vertical respectively; and, in the case where the oblique side of the wedge is next the bearing, an exactly horizontal movement will not be obtained. Neither is it necessary that the two directions of adjustment should be exactly at right angles to each other, although an approximation to a right angle is advantageous, as, otherwise, adjustment by the adjusting device may be partly counteracted by adjustment by the other adjusting device.

Although it is generally preferable to provide for adjusting the bearings of both side rollers as above described, my invention might be applied to the bearings of one side roller only.

What I claim as new and desire to secure by Letters Patent is:—

1. In a mill adapted for the crushing of sugar cane, a headstock, a bearing for the journal of a side crushing roller, a recess in the side of said headstock adapted to contain said bearing, a wedge block adapted to slide on the bottom of said recess and to support said bearing, a lower pinch screw adjustably supported for actuating said wedge block, a bolster block in contact with a ver-

tical side of said bearing, an upper pinch screw adjustably supported and bearing on said bolster block, said upper screw being adapted to effect a lateral adjustment of said bearing and said lower screw and wedge block effecting an up and down adjustment of said bearing.

2. In a mill adapted for the crushing of sugar cane, a top roller, two side rollers, 45 bearings for the journals of said side rollers, a cap for said bearings, a headstock having an inclined surface *g* under one of said side roller journals, said cap being secured to said headstock, a wedge block *h* supported on said surface *g*, said side roller journal bearing being located intermediate said wedge block and said side roller journal, a lower pinch screw adjustably mounted in said cap and in alinement with said wedge block, an upper pinch screw mounted above said wedge block, a nut *p* located in a recess in said cap through which nut said upper screw passes, and a bolster block intermediate said bearing and the end of said upper pinch screw, said bolster block being supported upon said wedge block, whereby said bearing is capable of lateral and vertical adjustments.

In testimony whereof I have signed my name to this specification in the presence of two subscribing witnesses.

HUGH WALLACE AITKEN.
